(57) **CLAIM**

The ornamental design for a balloon weight as shown and described.

DESCRIPTION

FIG. 1 is a front elevational view showing the claimed design;

FIG. 2 is a rear elevational view thereof;

FIG. 3 is a right-side elevational view thereof;

FIG. 4 is a left-side elevational view thereof;

FIG. 5 is a top plan view thereof;

FIG. 6 is a bottom plan view thereof; and,

FIG. 7 is a bottom and left-side perspective view thereof. In the drawings, the broken lines do not form a part of the design sought to be patented.
